COMBINED DRAPERY AND SHADE SUPPORT

Levi L. Henderson, Omaha, Nebr.

Application April 17, 1937, Serial No. 137,486

2 Claims. (Cl. 248—255)

The present invention relates to a fixture for supporting shade rollers and curtain and drapery rods on window casings.

An object of the invention is to provide a fixture of this character which may be more easily and quickly secured in position than present day fixtures, and which requires no nails, screws or the like which are hard to use and which require a certain amount of skill and which mar the surface of the window casing, particularly when the fixtures are changed or adjusted into different positions.

Another object of the invention is to provide a fixture which has the securing or clamping means as a part of the fixture structure; requiring no separate parts, which is easy and automatic in operation to secure the fixture in place, and which may be easily and quickly released when the fixture is to be removed.

A further object of the invention is to provide a simple, cheap construction embodying a pair of brackets for attachment to opposite sides of the window casing, each bracket embodying but a pair of one-piece relatively movable and interlocking parts having the necessary integral shade roller and curtain and drape rod engaging portions; the bracket being reversible so as to properly match the shade roller round and flat ends, without requiring special right and left brackets and the consequent care in the selection of the proper bracket for a particular side of the window casing.

A still further object of the invention is to provide a bracket structure which may be secured in position rigidly by a separate wedge or key cooperating with integral parts of the sections of the bracket.

With the foregoing and other objects in view, the invention will be more fully described hereinafter, and will be more particularly pointed out in the claims appended hereto.

In the drawings, wherein like symbols refer to like or corresponding parts through the several views.

Figure 1 is a front elevation, partly broken away of a window casing having a pair of the bracket fixtures of this invention applied thereto, the dotted lines showing a shade roller supported thereon.

Figure 2 is an enlarged horizontal section taken through one side of the window casing, showing one of the brackets applied thereto, and showing in dotted lines the adjacent end portions of a shade roller and curtain and drapery rods mounted on the bracket.

Figure 3 is an inner face view of one end of one of the bracket parts or members.

Figure 4 is an outer side elevation of the same.

Figure 5 is a like view of the other bracket part or member.

Figure 6 is an inner face view of the end of the bracket part of Figure 5.

Figure 7 is a fragmentary front elevation of a window casing having a modified form of bracket fixture applied thereto.

Figure 8 is an enlarged horizontal section taken through one side of the window casing, showing the modified form of bracket applied thereto and supporting a shade roller and rods for curtains and drapery.

Figure 9 is an outer side elevation of one of the modified bracket members.

Figure 10 is a like view of the other modified bracket member.

Figure 11 is a detail face view of the binding wedge or key of the modified form.

Figure 12 is an edge view of the latter.

Figure 13 is an outer end view of the modified bracket part of Figure 9, and

Figure 14 is a like view of the bracket part shown in Figure 10.

Referring now to the drawings, 20 designates the head of a window casing and 21 the sides thereof. The fixture comprises a pair of brackets, one adapted to be secured to each side 21 of the window casing and the brackets are of similar construction, being merely secured in reverse positions to match the opposite ends of a shade roller 22, shown in dotted lines in Figures 1, 2, 7 and 8.

Two forms of the bracket of this invention are shown in the drawings. In the first form, shown in Figures 1 to 6, the bracket comprises two cooperating parts or members 23 and 24 which may be stamped from strap metal. The part 23 has a body plate bent at substantially right angles at one end to provide a flange 25, the extremity of which is inturned and beveled to provide a spur or claw 26. It will be understood that the part 23 is formed of material having a desired degree of inherent resiliency, whereby adjacent the junction of the flange 25 with said part 23, said resiliency normally urges the spur or claw 26 toward the part 23 for purposes later described. The flange 25 also has on its outer side an outwardly pressed boss 27 having a round central opening or socket 28 to receive the round pintle of the shade roller 22. Struck outwardly from the body plate of the part 23 near the base of the flange 25 is a suit-

ably shaped arm 29 disposed at substantially right angles to the body plate for the reception of the inturned end of the outer drape rod 30, as shown in Figures 2 and 8. The body plate of the part 23 has a longitudinal central depression 31 extending through the opposite end of the plate, and series of spaced teeth or shoulder 32 are provided along the upper and lower edges of the depression by upsetting or in any other suitable manner.

The other part or member 24 of the bracket comprises a complementary body plate having on its outer end a right angularly bent flange 33 having an inturned spur or claw 34 on its end. Said other part or member 24 is also formed of metal having an adequate degree of inherent resiliency whereby the claw 34 of the flange 33 is, in use, normally urged toward the oppositely disposed claw 26 at the opposite side 21 of the window casing. The normal tendency of the claws 26 and 34 to spring towards each other cooperate to take up any slack incident from an imperfect fitting of a later described head 39 with certain later mentioned detent lugs or teeth 32. An outwardly pressed boss 35 is provided with a central slot 36 therein to receive the flat pintle end of the shade roller 22, said boss forming a part of the flange 33. The other end of the body plate of the part 24 is longitudinally slotted to provide a central tongue 37 and opposite edge fingers 38. The tongue 37 is offset outwardly at its base and has an inwardly bent T head 39 normally urged inwardly by the tongue 37 for operation substantially in the plane of the fingers 38. The body plate of the part 24 also has an outstanding arm 40 struck from the body plate to receive the inturned end of a curtain rod 41, as shown in Figures 2 and 8.

The body plates of the parts 23 and 24 are adapted to lie across the outer face of the side 21 of the window casing with the inner portions of the plate overlapping and interfitting. The fingers 38 of the part 24 engage in the guideways at opposite sides of the depression 31 and behind the body plate of the part 23 to maintain the parts 23 and 24 in alignment. The tongue 37 lies at the outer side of the depression and presses the T head 39 into engagement with the teeth 32 of the part 23, the teeth 32 and head 39 being relatively constructed so that the tongue may slide over the teeth as the bracket parts are forced together but which effect the interlocking of the teeth and tongue when the bracket parts 23 and 24 are urged apart to hold the bracket securely in clamped position.

The spurs 26 and 34 engage and bite into the edges of the side 21 of the window casing and hold the bracket securely in place without the use of nails, screws or other fastening means. The flanges 25 and 33, as well as the rod supporting arms 27 and 40 are relatively proportioned in length to compensate for the overlapping thicknesses of the parts 23 and 24 when in position across the face of the window casing side 21.

The bracket parts 23 and 24 are merely loosely assembled across the side 21 of the window casing at the desired height and with the parts turned to dispose either the round socket 28 or the slot socket 36 at the inner edge of the window casing to accommodate the adjacent end of the shade roller 22, when the bracket parts are pressed toward each other to relatively slide the body plates on each other and sink the claws or spurs 26 and 34 into the opposite edges of the window casing. During this compressing move-

ment of the parts 23 and 24 the spring tongue carried head 39 rides over the teeth 32 and holds the parts 23 and 24 from separation, and maintains the bracket firmly in place. To release the bracket, the head 39 is sprung outwardly from the teeth 32 when the parts may be readily pulled apart.

The brackets are used in pairs, and after a pair of the brackets are secured upon the sides 21 of the window casing the shade roller 22 and the curtain and drapery rods 41 and 30 may then be mounted on the arms 40 and 29, respectively.

In the modified form, shown in Figures 7 to 14, the body plates of the parts 23a and 24a are constructed at their outer ends similarly to the first form above described but at their inner overlapping ends are provided with outwardly extending lugs 42 and 43 serving as guides for the body plates and also as abutments for a wedge or key 44 used for drawing the parts 23a and 24a together into clamping position. The lug 42 is turned outwardly from the end of a tongue 45 which is an extension of the body plate 24a, and the lug 42 projects through a longitudinal slot 46 provided in the other body plate of the part 23a, the lug 42 having a sliding fit in the slot 46 to hold the plates in overlapping registering position. The opposed lug 43 is struck out of one end of the slot 46 of the part 23a and extends outwardly therefrom, the lugs 42 and 43 being bent in downwardly converging planes to receive and support therebetween the tapering key or wedge 44. The key 44 may have roughened opposite edges, Figure 11, to hold the key from moving out of the space between the lugs 42 and 43 unless sufficient force is exerted on the key to loosen it. The larger end of the key 44 may have a laterally bent flange 47 for receiving pressure or impact from a hammer or other tool, or even by the hand to force the key into binding position between the lugs 42 and 43 for spreading the same and drawing the body plates of the bracket parts 23a and 24a into overlapping relation and securing the bracket on the side 21 of the window casing. The slot 46 in the part 23a is of sufficient length to admit free sliding of the lug 42 therein during adjustment and clamping of the bracket to the window casing.

The modified form is otherwise constructed and used similarly to the first described form, and requires only the key 44 as a separate part for effecting the attachment of the bracket in place.

The arms 29 and 40 of the modified form together with the similar arms of the preferred construction are T-shaped in plan, as shown in Figures 3, 6, 13 and 4, the heads of the T's each having a longer leg A and a shorter leg B which are of particular advantage in securing outer drape rods 30 and curtain rods 41 thereto. Said rods are of conventional extensible construction and provided with two apertures closely adjacent each end thereof, whereby to apply said rods to said arms the longer legs A are first caused to extend through an aperture and the leg B next secured through the other aperture, the arcuate edges of the legs B facilitating the operation. When attaching said legs extend through the rods. By this means the rods are readily secured to the arms in a removable manner.

It is obvious that various changes and modifications may be made in the details of construction and design of the above specifically described embodiment of this invention without departing from the spirit thereof, such changes

and modifications being restricted only by the scope of the following claims.

What is claimed is:

1. A shade and curtain fixture comprising a pair of similar brackets for attachment to the opposite sides of a window casing, each bracket having a pair of body plates adapted to be overlapped at their inner ends, each body plate having a backwardly bent flange at its outer end and an inturned claw on the flange for biting engagement in the adjacent edge of the side of the window casing, each flange also having an outwardly pressed boss with a pintle socket therein for receiving the adjacent end 10 pintle of a window shade, said body plates having outwardly struck fingers adjacent their outer ends for receiving the adjacent ends of curtain and drapery rods, and means for securing the body plates in overlapping relation and with the 15 claws in clamping position on the edges of the side of the window casing.

2. A shade and curtain fixture comprising a

pair of similar brackets for attachment to the opposite sides of a window casing, each bracket having a pair of body plates adapted to be overlapped at their inner ends, each body plate having a backwardly bent flange at its outer end and an inturned claw on the flange for biting engagement in the adjacent edge of the side of the window casing, each flange also having an outwardly pressed boss with a pintle socket therein for receiving the adjacent end pintle of a window shade, said body plates having outwardly struck fingers adjacent their outer ends for receiving the adjacent ends of curtain and drapery rods, the overlapping portions of said body plates having outturned lugs and the outer body plate having a slot therein for the reception of the lug of the inner body plate, and a wedge for engagement between the lugs for spreading the same to bind the bracket on a window casing.
